THOMAS M. MANSON AND CHARLES H. WARD, OF TORONTO, ONTARIO, CANADA, AS
SIGNORS TO CLEAR VISION PUMP COMPANY, LIMITED, OF TORONTO, CANADA.

LIQUID DISPENSER.

Application filed February 3, 1927. Serial No. 165,598.

The principal objects of the invention are, to simplify the construction and to effect a material reduction in the cost, and to provide a device which will be very simple and easy to operate and which will effectively protect the customer against fraud and dishonesty on the part of the operator.

A further important object is to enable the accurate adjustment of the overflow to determine the proper level of the liquid at the top measuring graduation.

The principal features of the invention consist in effecting a siphonic draining of the liquid from a measuring bowl back to the supply and in the novel construction and arrangement of parts, whereby the siphonic action is manually controlled, and whereby the drain pipe for regulating the maximum height of the liquid in the measuring bowl may be accurately adjusted to register with the scale graduations on the bowl.

In the drawings, Figure 1 is a longitudinal vertical sectional view of a liquid dispenser constructed in accordance with this invention.

Figure 2 is an enlarged longitudinal mid-sectional view of the siphon overflow and air release.

Figure 3 is an enlarged sectional perspective detail of the upper end of the overflow siphon and siphon operating valve.

In the visible type of liquid dispensers it is customary to arrange some form of device for draining the liquid from the measuring bowl when business is suspended, in fact, this is a very rigid requirement of insurance conditions.

In the pumps at present on the market the draining of the bowl is effected by the opening of a valve which requires considerable equipment which is dispensed with in the present device.

In the construction herein shown, the standard casing 1 is of the usual tapered form carrying a cast metal cap 2 upon which is mounted the glass measuring bowl 3.

The upper end of the measuring bowl is sealed by a cap 4.

The cap 2 is preferably cast with a pocket 5 therein arranged off centre and extending downwardly from said pocket is the drain pipe 6 which leads back to the liquid supply reservoir.

Offset from the drain pipe and in the upper

side of the cap 2 is arranged an orifice 7 in which is secured a packing gland 8.

A tube 9 extends upwardly from said packing gland and forms the overflow, the top end of which is arranged level with the maximum gauge marks on the bowl.

Mounted on the upper end of the tube 9 and supported thereabove by the lugs 10 is a valve casing 11 which is provided with a lateral annular flange 12 and to this flange is secured a tube 13 which is of considerably greater diameter than the tube 9 and extends downwardly to a point close to the top of the packing gland 8.

The tube 13, together with the valve casing 11 which is closed on top, forms a bowl or chamber and the tube 9 arranged within the tube 13 being spaced below the flange 12 by the lugs 10 forms a siphon tube so that if a column of liquid is elevated within the tube 13 to overflow into the tube 9, a siphonic action is produced, which results in the draining of the bowl through the siphon.

The upper cap 4 is sealed in an air tight joint on the top of the bowl 3 as mentioned and an air valve 14 is arranged in the top of said cap, said air valve having an orifice 15 leading to a plunger chamber 16 from the interior of the bowl and a plunger 17 seats in a tapered seat 18 leading to the air inlet opening 19.

In the normal action of the bowl in measuring liquids the liquid is drawn off through the dispensing tube 20 and air flows into the bowl 3 through the inlet opening 19 past the plunger 17 but if an internal pressure is created within the bowl, the pressure automatically closes the plunger 17 against its seat.

A rotary valve 21 is arranged within the valve casing 11 arranged at the top of the siphon tube. This valve is of a very simple type having a peripheral opening 22 which upon the rotation of the valve may be brought into, or moved out of register with the opening 23 in the side wall of the casing 11.

The top plate 24 which secures the valve 21 within the casing is provided with a quadrant slot 25 in which a pin 26 secured to the valve is adapted to travel. This pin and slot form a positive limitation for rotation of the valve.

The valve 21 is open at the bottom end and

is provided with a cross bar 27 to which is secured a spindle 28.

The spindle extends downwardly through the tube 9 and through a packing gland 29, in the bottom of the pocket 5.

An operating lever 30 is secured to the lower end of the spindle 28 which extends below the pocket 5 and said lever extends out through a slot 31 in the casing 1.

10 The operator of the pump by manipulating the lever 30 may open or close the valve 21. When said valve is closed and liquid is pumped into the bowl through the supply pipe 32 leading from the pump 33 a pressure of air is created in the bowl automatically closing the plunger valve 17, consequently the pressure between the cap 4 and the top of the liquid in the bowl forces the liquid up inside of the tube 13 around the tube 9, until the liquid overflows the top of the tube 9.

15 A siphon is instantly created by this action and the remaining contents of the bowl will be carried up the tube 13 and discharged through the tube 9, the pocket 5 and the drain pipe 6 leading therefrom back to the supply reservoir.

20 In the ordinary operation of the pump the valve 21 remains open with the opening 22 in the valve opposite the opening 23 in the valve casing, consequently the volume of air in the bowl will simply flow through the valve down into the overflow tube as the bowl is filled.

25 The air valve 14 allows the ingress of air to the bowl to prevent any retarding of the liquid through the ordinary dispensing tube 20.

30 It will be understood from this description that a single overflow tube without any valve mechanism to be fitted therein extends between the bowl and the connection to the reservoir.

35 The siphon equipment is very simple. It is readily assembled in the bowl top and operates very simply.

40 In order to adjust the overflow tube 9 a plate 34 is secured to the top of the plate 24. The plate 34 is provided with a recessed opening 35 in which is housed the head 36 of a screw spindle 37. The spindle extends upwardly through and is threaded in the packing gland 38 in the top cap. It is therefore only necessary to rotate the spindle to raise or lower the tube 9 which slides freely in the lower packing gland 8.

45 The construction of the apparatus is greatly simplified. The number of parts are reduced to the minimum and as the dispensing of the drain valve eliminates the necessity of doors, locks and other forms of apparatus necessary where any mechanism within the standard requires to be available of access.

50 With the construction of device described the operator may drain the contents of the bowl back to the supply reservoir, irrespec-

tive of the level of liquid in the bowl, by simply closing the valve 21 and forcing a small quantity of liquid into the bowl. This creates a pressure and raises the liquid in the siphon tube to start the siphonic action. 70

What we claim as our invention is:—

1. A liquid dispenser, comprising a sealed measuring chamber having a liquid inlet and an overflow tube, a tube open at the bottom extending over said overflow and enclosing the top thereof, said tubes communicating at their upper ends, a valve in the top of said enclosing tube to admit air thereto from the top of the chamber or exclude the passage of air therethrough, and an air valve in the top of said chamber adapted to allow the ingress of air but to exclude egress of air therethrough. 75

2. A liquid dispenser, comprising a measuring chamber having an inlet pipe extending upwardly from the bottom, an overflow tube extending through the bottom of said chamber and having an open upper end, a pipe connected with the lower end of said overflow tube adapted to conduct the overflow therefrom, a tube suspended over said overflow tube being open at the bottom and having a valve at the top adapted to be opened or closed, said tubes communicating at their upper ends below the valve, a spindle operating said valve, and means extending beyond the interior of said measuring chamber for turning said spindle to open or close said valve. 80

3. A liquid dispenser, comprising a closed measuring chamber, a drain tube leading from said chamber, an overflow extension from said drain tube extending upwardly into said chamber and having an open upper end, an outer tube having a valve at its upper 105 end extending downwardly over the overflow extension tube within the chamber, said outer tube and extension being connected below said valve and means extending beyond the chamber for controlling said valve. 110

4. A liquid dispenser, comprising a measuring casing, a drain tube leading from the bottom of said casing to conduct the overflow therefrom, an overflow tube extending upwardly from said conducting tube into said 115 casing and vertically adjustable therein, said overflow tube being open at the upper end, adjustable means for supporting said overflow tube from its upper end, a tube extending downwardly over the open end of the 120 overflow tube, and having its upper end connected with the open upper end of the overflow tube, a valve arranged at the upper end of the outer tube, and means for opening and closing said valve. 125

5. A liquid dispenser, comprising a tubular standard, a sealed measuring chamber arranged on top of said standard, an overflow tube adjustably suspended from the top of said sealed chamber and slidably extending 130

through the bottom thereof, a pipe leading from the bottom of said overflow tube, a tube extending over the open end of said overflow tube and connected at its upper end to the interior of the overflow tube said latter tube having a valve closing the top thereof to admit air thereto or exclude air therefrom, a feed pipe leading into said chamber, a discharge pipe leading from the bottom of said chamber, and an air valve arranged in the top of said chamber.

6. A liquid dispenser, comprising a tubular standard, a cap arranged on the top of said tubular standard having a pocket therein, a drain pipe leading from said pocket, a packing gland arranged in the top of said pocket offset from said drain pipe, a tube centered in said packing gland and open at the top, means connected to the upper end of said tube for raising and lowering same, a closed measuring bowl mounted on said cap, a cap sealing the stop of said measuring bowl, a tube supported from said sealing cap and extending over the top of said overflow tube and having its lower end arranged slightly above the bottom of the chamber enclosed within the bowl, said tubes communicating at their upper ends, a valve arranged at the upper end of the latter tube, a spindle operating said valve extending down through the overflow tube and through said pocket, and a lever secured to said spindle and extending outwardly through the tubular standard.

7. A liquid dispenser, comprising a tubular standard, a sealed measuring bowl supported on said standard, a drain pipe connected with the bottom of said bowl, an overflow pipe leading to said drain pipe, a valve casing having downwardly depending lugs secured to said overflow pipe, a tube secured to said valve casing and spaced from said overflow pipe and extending downwardly thereover and enclosing the upper end thereof and being open at the lower end, said overflow pipe and tube communicating at their upper ends, a rotary valve enclosed within said casing having an opening in the side wall, an opening in the side wall of the casing adapted to register with the opening in said valve, a spindle connected with said valve extending beyond the sealed casing, means for rotating said spindle, means for raising and lowering said overflow tube, an air valve in the top of said sealed casing, an inlet opening into said sealed casing, and a discharge leading from the bottom of said sealed casing.

8. A liquid dispenser, comprising a base, a tubular standard mounted on said base, a sealed measuring chamber mounted on said standard, a fluid pump arranged on the base, a feed pipe leading from the fluid pump into said sealed chamber, a discharge pipe leading from the bottom of the sealed chamber, a drain pipe leading from the bottom of said

sealed chamber, an overflow pipe connected with said drain pipe and extending upwardly into said chamber, a tube extending over the open end of said overflow pipe, and having its upper end connected with the upper end of said overflow pipe, a valve arranged in the upper end of the latter tube, means extending beyond the sealed chamber for operating said valve, and an air inlet valve arranged in the top of said chamber.

9. In a liquid dispenser, the combination with a measuring chamber and an overflow, of means for temporarily closing the overflow entrance, and means connecting the chamber with said overflow and adapted to form therewith a siphon to withdraw the liquid from the chamber when the overflow entrance is closed.

10. In a liquid dispenser, the combination with a measuring chamber and an overflow tube arranged therein, of a tube encircling the upper end of the overflow tube, said tubes communicating at their upper ends and adapted upon the closing of the overflow entrance to form a siphon to empty the measuring bowl, and means for temporarily closing the entrance to said overflow tube to complete the siphon.

11. In a liquid dispenser, the combination with a measuring chamber and an overflow tube arranged therein, of a tube encircling the end of said overflow tube within the chamber, said tubes communicating at their upper ends and being adapted upon the closing of the entrance to said overflow tube to form a siphon to empty the contents of the measuring chamber, a valve arranged in the entrance to the overflow tube and adapted to close the same against the egress of air from the measuring chamber and complete the siphon, said valve being adapted when opened to allow air to escape from said chamber, and means for opening and closing said valve.

12. In a liquid dispenser, the combination with a measuring chamber, a supply, and an overflow leading from the upper end of the measuring chamber and connected with the supply, of means connecting said overflow with the lower end of the measuring chamber and forming with said overflow a siphon for siphoning the liquid from said measuring chamber to return it to the supply.

13. In a liquid dispenser, the combination with a supply tank, a measuring chamber, and a return pipe from said measuring chamber leading to said supply tank and normally receiving the overflow from said chamber, of auxiliary means connected with said overflow and forming therewith a siphon for siphoning the contents of the measuring chamber through said return pipe to the supply tank.
